(57) CLAIM

The ornamental design for a lamp, as shown and described.

DESCRIPTION

FIG. 1 is a rear, right side and top perspective view of a lamp showing my new design;

FIG. 2 is a rear, left side, bottom perspective view thereof;

FIG. 3 is a bottom view thereof;

FIG. 4 is a top view thereof;

FIG. 5 is a right side view thereof;

FIG. 6 is a left side view thereof;

FIG. 7 is a rear view thereof; and,

FIG. 8 is a front view thereof.

The broken lines in the drawings illustrate portions of the lamp that form no part of the claimed design.
